R. HITCHCOCK

SOCKET FOR INCANDESCENT LAMPS

Filed March 27, 1922

Inventor:
Ralph Hitchcock,
by *Alfred H. Davis*
His Attorney

UNITED STATES PATENT OFFICE.

RALPH HITCHCOCK, OF PITTSFIELD, MASSACHUSETTS, ASSIGNOR TO GENERAL ELECTRIC COMPANY, A CORPORATION OF NEW YORK.

SOCKET FOR INCANDESCENT LAMPS.

Application filed March 27, 1922. Serial No. 547,154.

The present invention relates to incandescent electric lighting, and more especially to sockets for decorative lighting.

The object of the invention is to provide an improved construction of decorative socket which shall be very hardy, of few parts, and adapted to be connected to electric conductors with facility.

One form of the invention is shown in the accompanying drawing, in which Fig. 1 is a side elevation of the complete socket; Fig. 2 is an axial section of the same; Fig. 3 is a perspective view of the anchor yoke for securing the electric contacts within the socket shell, and Fig. 4 is a similar view of the electric contacts.

The outer shell 1 is moulded of insulating material in the form of a bell with a central aperture 2 at the top for passage of the flexible conductors 3, a substantial holding and strengthening bead 4 at the lower end, and a cavity 5 with substantially cylindrical walls.

The electric contacts comprise a screw shell contact 6 and a center contact 7 adapted to engage respectively with the usual contacts on the base of an incandescent lamp (not shown). The screw shell contact 6 is in the form of a sheet metal cylinder with a coarse thread 8 impressed in the main portion thereof, an outwardly flaring flange 9 at the lower end of sufficient size to close the end of the central cavity 5 in the outer shell, and with its upper end spun over the periphery of an insulating washer 10. The center contact 7 is in the form of an eyelet extending through the center of the insulating washer 10 and upset about the adjacent shoulders thereof. The two contacts 6 and 7 and the washer 10 thus form a unitary structure, as indicated in Fig. 4.

The means for securing the unitary contact structure within the cavity 5 of the outer insulating shell 1 consists of an anchor yoke 11, as shown in Fig. 3, and made of a sheet metal punching having a ring portion 12 and a plurality of flexible arms 13 bent up from the periphery thereof and with their free ends inclined outwardly. The upper end of the screw shell contact 6 is adapted to enter and receive the ring portions 12, while the arms 13 extend freely over the threaded portion thereof. When connecting the socket to the flexible conductors 3, the latter are threaded through the

central aperture 2 in the outer shell 1 and pulled through for several inches so that the shell will not interfere with the other assembling operations. One wire is soldered to the screw shell contact 6 at the level 60 of the anchor ring 12 so that the latter is simultaneously attached to the screw shell, and the other wire is entered in and soldered to the eyelet constituting the center contact 7. By pulling upon the wires 3 and forcing the outer shell down, the contact unit will be forced home therein and frictionally retained by means of the arms 13 engaging and indenting the wall of the cavity thereof. When it is desired to make the socket 70 weatherproof, the unoccupied space between the contact unit and the cavity wall is filled with pitch poured while hot through the central aperture 2.

While I have shown and described the 75 best embodiment of the invention known to me, I do not desire to be restricted thereto.

What I claim as new and desire to secure by Letters Patent of the United States, is:—

1. In a lamp socket, the combination of 80 an outer shell of insulating material having a cavity extending therein from one end, a screw shell contact adapted to enter said cavity and having a continuous end flange adapted to engage the end wall of said outer 85 shell, a center contact connected to said screw shell through insulation, and flexible arms disposed between said screw shell and the side wall of said cavity for frictionally anchoring the screw shell in said cavity. 90

2. In a lamp socket, the combination of 95 an outer shell having a cavity therein, a screw shell contact, and a ring yoke connected to said contact and having a plurality of arms engaging the wall of said cavity. 105

3. In a lamp socket, the combination of 100 an outer shell of moulded insulating material having a cavity therein, a screw shell contact having at one end a flange adapted to engage the end wall about said cavity and at its other end an insulating washer secured thereto, an eyelet contact secured in said insulating washer, and an anchor yoke comprising a ring surrounding and attached to said screw shell contact and provided with 105 a plurality of flexible arms adapted to engage the wall of said cavity.

In witness whereof, I have hereunto set my hand this 24th day of March 1922.

RALPH HITCHCOCK.
